UNITED STATES PATENT OFFICE.

FRANKLIN M. SMILEY, OF GOSHEN, INDIANA.

DRAFT-EVENER.

1,264,698.

Specification of Letters Patent. Patented Apr. 30, 1918.

Application filed April 2, 1917. Serial No. 159,181.

To all whom it may concern:

Be it known that I, FRANKLIN M. SMILEY, a citizen of the United States, residing at Goshen, in the county of Elkhart and State 5 of Indiana, have invented new and useful Improvements in Draft-Eveners, of which the following is a specification.

My present invention pertains to draft eveners, and will be fully understood from 10 the following description and claims when the same are read in connection with the drawings, accompanying and forming part of this specification, in which:

Figure 1 is a plan illustrating an evener 15 constructed in accordance with my invention.

Fig. 2 is a section taken in the plane indicated by the line 2—2 of Fig. 1, looking rearwardly.

Fig. 3 is a detail section taken on the line 20 3—3 of Fig. 1.

Similar numerals of reference designate corresponding parts in all of the views of the drawings.

The main bar 1 of the evener is shown as 25 provided adjacent to its outer end with a swing-tree 2, and the comparatively short member 3, formed by parallel bars, is arranged with its inner portion disposed in 30 lapped relation to and in front of the inner portion of said bar 1. The said member 3 is shown as equipped with a double-tree 4, and it is pivotally connected with the bar 1 through the medium of a bolt 5, which 35 bears in a plate 5^a, fixed to the forward side of the bar 1. The said bolt 5 also serves for the connection of the inner ends of plates 6, Figs. 1 and 2, the outer ends of which 40 are connected by rivets 7 to the bars of the member 3 so that the plates will move as a unit with the member 3. In the plates 6 are slots 8, and disposed and movable in the said slots is a bolt 9 through which a 45 clevis 10 is connected with the plates. At its rear end the clevis 10 is pivotally connected to and adapted to swing vertically on a link 11, which, in turn, is pivotally connected to and adapted to swing horizontally 50 on a clevis head 12 at the forward end of a plow beam, indicated by 13.

A stay 14 is pivotally connected at 55 to the end of a strap 15^a which is fixed to the front side of the bar 1, the said pivotal connection being at the inner end of the bar 1. The said stay 14 is arranged with its rear end disposed at the inner side of an

angle plate 16—i. e., between the inner arm of said plate and the clevis 10; the outer arm of the angle plate 16 bearing against the forward edge of the clevis head 12. It 60 will also be noted that the stay 14 is adapted to bear at its rear end against the forward edge of the clevis head 12.

It will be manifest from the foregoing 65 that when one team pulls at the outer end of bar 1 and another team at the outer end of the member 3, the fulcrum will be the pivot point or connection 15, and the base for the fulcrum will be the point at which the stay 14 bears against the clevis head 12, 70 while the load point or point of weight will be the bolt 9. From this it follows that the draft will be efficiently equalized between the draft animals.

By the use of my evener with its system 75 of levers, the clevis may be adjusted at the center of the plow and permit the team to travel with one horse in the furrow and the others on the unplowed ground, all of them walking straight ahead with plenty of room 80 for their comfort. By this means, not only is the team made more comfortable, but by adjusting the clevis at the center of the plow it is drawn as it is intended to be drawn, and in consequence the draft is very 85 materially reduced, and it does its work much better. And, moreover, the evener can be so adjusted as to permit of the use of either three or four horses without changing 90 the adjustments of the plow.

As shown in Fig. 1 the long bar 1 and the short member 3 are provided with apertures at intervals so that by adjustment of the trees the evener can be used to advantage with three, four or five horses. I 95 would also have it understood that by simply turning the evener upside down the evener may be converted from a right hand evener to a left-hand evener and vice versa; it being understood that the evener is of 100 the left-hand type when the long bar is toward the right and is a right-hand evener when the long bar is toward the left.

By virtue of the slots 8 being provided in the plates 6 which are fixed to the member 3, weakening of the said bar is prevented.

It will be gathered from the foregoing 110 that notwithstanding the practical merit of my novel evener in operation, the construction is simple and inexpensive and is well adapted to withstand the rough usage to

which devices of corresponding type are ordinarily subjected.

Having described my invention, what I claim and desire to secure by Letters-Patent, is:

1. In a draft evener, the combination of a device to be drawn, a long bar arranged with its inner portion in front of and in substantial parallel relation to said device, a short member, a pivotal connection between the inner portions of the long bar and the short member, a stay connected with the inner end of the long bar and arranged with its rear end bearing against the device to be drawn, 10 a clevis connected at one end to the device to be drawn and at its opposite end to the short member at a point between the point at which the short member is pivotally connected to the long bar and the point where 15 the stay is connected to the inner end of the long bar, and confining means on the device to be drawn, arranged at the opposite side of the stay, with reference to the clevis.
2. In a draft evener, a clevis head, a clevis 20 connected therewith, confining means on the head and spaced from the clevis, a long bar, a stay pivotally connected to the inner end of the long bar and bearing at its rear end against the clevis head at a point between 25 the clevis and the confining means, and a

short member pivotally connected at its inner end with the long bar at an intermediate point in the length of the latter and connected to the clevis at a point between the connection of the stay to the long bar 35 and the connection of the short member to said bar.

3. In a draft evener, a clevis head, a clevis connected therewith, confining means on the head and spaced from the clevis, a long bar, 40 a stay pivotally connected to the inner end of the long bar and bearing at its rear end against the clevis head at a point between the clevis and the confining means, a short member pivotally connected at its inner end 45 with the long bar at an intermediate point in the length of the latter and having a slot at a point between the connection of the stay to the long bar and the connection of the short member to said bar, and a bolt movable 50 in said slot and connecting the clevis with the short member.

In testimony whereof I have hereunto set my hand in presence of two subscribing witnesses.

FRANKLIN M. SMILEY.
